UNITED STATES PATENT OFFICE.

KONRAD ROSSLER, OF FORT WORTH, TEXAS.

SHEARS-SHARPENER.

SPECIFICATION forming part of Letters Patent No. 657,619, dated September 11, 1900.

Application filed April 10, 1900. Serial No. 12,376. (No model.)

To all whom it may concern:

Be it known that I, KONRAD ROSSLER, a citizen of the United States, residing at Fort Worth, Texas, have invented a new and Improved Shears-Sharpener, of which the following is a specification.

My invention relates to devices for sharpening shears, and more particularly to a clamp for holding the shears in position to be operated on by a suitable hone; and the object is to produce a device for sharpening shears or scissors or other objects and which can be manufactured at small cost and which can be put up in a small package.

15 The sharpener is designed for fine work on shears and other tools.

Other objects and advantages will be fully understood from the following description and claims.

20 Reference is had to the accompanying drawings, which form a part of this application.

Figure 1 is a side elevation of the invention, showing a section of scissors-blade clamped in position to be operated upon. Fig. 2 is a 25 plan view of the invention, showing a pair of scissors in place for sharpening. Fig. 3 is a portion of a blade, illustrating the strokes of the hone on the blade. Fig. 4 illustrates a variation of the clamp, the nut and the washer being shown in vertical section. Fig. 5 illustrates another variation of the clamp, the nut and the movable jaw being shown in vertical section.

30 Similar characters of reference are used to indicate the same parts throughout the several views.

This invention consists of a body 1, having an arm 2 and a jaw 3 and an upper jaw 4, loosely attached to the body by a loose rivet 40 5. The two jaws are shown engaging a scissors-blade 6 in Fig. 2. The upper jaw 4 is secured on the blade by a thumb-screw 7. The bevel-setter 9 is secured to the arm 2 by means of the thumb-screw 8. The hone 10 45 is provided with a guide-rod 11. This guide-rod passes through a hole in the bevel-setter 9 and works loosely therein. The sharpener may be secured to a work-bench or desk or table by the screws 12.

50 The variation shown in Fig. 4 consists of the body 13 having the upper jaw 14 integral therewith, and having the end 15 thread-

ed and provided with a nut 16 and a cone-shaped washer 17. The nut 16 is adapted to press a scissors-blade 18 against the upper jaw 14. The body 13 is provided with an arm 19, similar to arm 2 of the form shown in Figs. 1 and 2.

The variation shown in Fig. 5 consists of the cylindrical body 20, having the arm 21, 60 the jaw 22, the movable upper jaw 23, and a nut 24 for controlling the upper jaw 23. The upper jaw 23 has a sleeve 25, which engages a shank of the body 20. A portion of the body 20 is threaded, on which the nut 24 65 moves to operate the upper jaw 23. A lug 26 is inserted in or made integral with the shank of the body 20, and a slot 27 is made in the sleeve 25. This lug will prevent the upper jaw from turning.

I have shown a sharpener which is capable of accomplishing the finest work on such instruments as barbers' and surgeons' shears. The bevel from the cutting edges can be ground to any desirable angle. The angle 75 which the bevel makes with the flat edge of a blade can be made slight or it can be made great. For general domestic work the bevel must be made at almost right angles to the flat surface. Barbers want the angle much 80 smaller, so that the blade will have what is known as a "keen" edge. The angle is increased by elevating the guide 11 of the hone. If the bevel-setter 9 is not high enough, a higher one may be used. The angle is diminished by lowering the setter 9. The setter can be placed in an upright position or at any position between the upright and a horizontal position. Fig. 1 shows the setter in an upright position, and Fig. 2 shows the setter 90 turned considerably to one side. The position in Fig. 2 will make the angle which the bevel makes with the flat surface of the blade much smaller than the position in Fig. 1 and the edge will be keener. This setting of the 95 bevel also regulates to some extent the strokes of the hone on the bevel. The strokes are biased toward the rivet of the blades, as shown in Figs. 2 and 3, the bias being greater in Fig. 3. The strokes of the hone make 100 teeth on the bevel, which teeth may be seen with a microscope. The teeth will resemble file-teeth. The object in having the teeth biased toward the rivet is to prevent hair or

other objects from slipping on the edges of the blades. If the teeth were biased toward the point of the blade, the object to be cut would slip or slide along the edge of the blade.

5 The bias can be further regulated by clamping the blade nearer or farther from the point of the blade. When the teeth point toward the rivet, the object to be cut will be pressed against the points of the teeth; but if the teeth pointed toward the points of the blades the object to be cut would be pressed against the sides of the teeth. The strokes must be inclined or biased toward the rivet when the hone is moving toward the flat surface of the 15 blade, and they must be inclined or biased toward the point of the blade when the hone is moving toward the round or convex surface of the blade.

Having fully described my invention, what 20 I claim as new, and desire to secure by Letters Patent, is—

1. A sharpener for shears comprising a body having a jaw integral therewith and another jaw adapted to engage and hold a blade 25 of the shears against said first-named jaw, a hone, and means at the other end of said body

for determining the angle which the hone makes with the flat surface of the blade and for regulating the strokes of the hone on the bevel of the blade.

30

2. A sharpener for shears comprising a body having an arm at one end and a jaw at the other end, an upper jaw, a loose rivet for securing the upper jaw on said body, a thumb-screw for clamping said jaws on a blade of 35 the shears, a bevel-setter mounted on said arm, and a hone provided with a guide-rod operating through said bevel-setter.

3. A sharpener for shears and other tools comprising a body provided with means for 40 holding rigidly a blade of the shears, means mounted on said body for giving any desired bevel to the blade and for biasing the stroke of the hone on the bevel, and the hone for sharpening the blade.

45

In testimony whereof I set my hand, in the presence of two witnesses, this 6th day of April, 1900.

KONRAD ROSSLER.
